Primary Examiner — Austin Murphy(74) *Attorney, Agent, or Firm* — Mintz Levin Cohn Ferris Glovsky and Popeo, P.C.(57) **CLAIM**

The ornamental design for a kiosk system, as shown and described.

DESCRIPTION

FIG. 1 is a top, front, and right side perspective of a kiosk system embodying my new design.

FIG. 2 is a front view thereof;

FIG. 3 is a back thereof;

FIG. 4 is a right side view thereof;

FIG. 5 is a left side view thereof;

FIG. 6 is a bottom view thereof; and,

FIG. 7 is a top view thereof.

Shown in phantom lines are grill features of the kiosk system which form no part of the claimed design.

1 Claim, 6 Drawing Sheets(56)
